UNITED STATES PATENT OFFICE.

DANIEL S. WAUGH, OF DENVER, COLORADO, ASSIGNOR TO THE DENVER ROCK DRILL MANUFACTURING COMPANY, OF DENVER, COLORADO, A CORPORATION OF DELAWARE.

ROCK-DRILL.

1,112,398.

Specification of Letters Patent. Patented Sept. 29, 1914.

Original application filed February 14, 1914, Serial No. 818,644. Divided and this application filed April 13, 1914. Serial No. 831,530.

To all whom it may concern:

Be it known that I, DANIEL S. WAUGH, a citizen of the United States, residing at Denver, in the county of Denver and State of Colorado, have invented new and useful Improvements in Rock-Drills, of which the following is a specification.

The present invention relates to drilling apparatus of the type employing expansive motive fluid, and preferably air as the actuating agency. In this type of machine, the employment of pneumatic feeding means is well known, said feeding means comprising a cylinder and a piston operating therein, one being connected to the motor, the other having a bearing against the rock or other supporting surface. It has also been common to provide a clamp for one of these members. While this feeding means has proven successful under certain conditions, one difficulty has been encountered, in that the machine can only be successfully used for drilling holes in substantially one direction. That is to say, a machine which will be held to its work for drilling an up-hole, heretofore has not been successful for drilling down holes. This, it is believed, will be obvious when it is considered that in drilling an upwardly extending hole, the area of the feed piston must be sufficient to support the weight of the machine in addition to resisting the blow of the tool against the rock. When, therefore, the machine is reversed to drill a down-hole, the weight of the machine in addition to the pressure against the feed piston causes the same to exert too great a pressure. It is therefore difficult, if not impossible, to rotate the machine and the drill bit is apt to become stuck, particularly in drilling soft and seamy rock.

The object of the present invention is to provide a machine, in which this serious difficulty is entirely overcome, and experience has demonstrated that it will operate with substantially the same freedom and effectiveness in drilling a down-hole as in drilling an up-hole.

The present application is in the nature of a division of my earlier application, Serial No. 818,644, which covers the drill hole cleaning mechanism.

An embodiment of the invention that has

proven entirely satisfactory in actual operation is disclosed in the accompanying drawings, wherein:

Figure 1 is a longitudinal sectional view through the machine, and Fig. 2 is a detail sectional view through the rear portion of the motor, illustrating the ports that control the supply of motive fluid to the front piston chamber in rear of the enlarged piston head.

Similar reference numerals designate corresponding parts in all the figures of the drawings.

In the embodiment disclosed, the motor is designated generally by the reference numeral 3, and the feeding means in like manner is designated 4. The motor is of the "valveless" type, and comprises a cylinder member 5 having a front chamber 6 and a rear chamber 7, the latter being of less diameter than the chamber 6, and being formed in a plug 8, suitably located in the rear portion of the cylinder member and held in place by a rear head block 9 that engages a flange 10 formed upon the plug 8, this flange 10 being confined between the head block 9 and the rear end of the cylinder member 5. A front head block 11 has suitably secured therein a chuck sleeve 12 that loosely receives the usual drill bit 13, and located in said head block 11 in rear of the chuck sleeve 12, is a tappet 14.

A reciprocating hammer piston operates in the cylinder member and comprises a front head 15 operating in the piston chamber 6 and a rear smaller elongated head 16 that operates in the rear chamber 7. These two heads are connected by a reduced neck 18 forming an annular groove 19. As a result of this construction, the piston has two separate rear pressure areas, one of which is designated 20, the other being designated 21, the said piston also having a front pressure area 22, which is equal to the combined areas 20 and 21.

The rear head block 9 has a rearwardly extending externally tapered extension 23 and said head block and extension have formed therein a motive fluid chamber 24 that is in constant communication with the smaller piston chamber 7. Formed in the plug 8, and communicating with the cham-

- ber 24, are supply ports 25 that open through the side walls of the smaller piston chamber 7, and are thus controlled by the piston head 16. Another supply passage 5 26 also opens through the side walls of the piston chamber 7, as illustrated at 27, and said passage leads to the front end of the forward piston chamber 6; in advance of the head 15, the port being designated 28.
- 10 An exhaust passage 29 is formed in one side of the cylinder member 5, and communicates with an annular groove 30 formed in the wall of the enlarged front piston chamber 6, the head 15 passing on opposite sides 15 of the groove, and thus permitting the alternate exhaust from the chamber 6 on opposite sides of the piston head 15.

The feeding means 4, in the present embodiment, consists of a cylinder member 31, 20 within which operates a piston member comprising a head 32 carried by a tubular piston rod 33 and having a packing cup 34 that is held to said head by a washer 35 and a plug 36 extending through the washer and 25 threaded into the head. The tubular piston rod 33 has a flared front end 37 that fits upon the tapered extension 23 of the head block 9, and surrounding this flared end is a collar 38 held in place by side bolts 39 30 passing therethrough, said side bolts connecting the collar 38 with the front head 11, and thus serving to hold all the parts in assembled relation. The head 32 of the feed piston, the packing cup 34 and the washer 35 are provided with passageways 40 that 35 afford communication from the rear of the feed piston through the same with the interior of the piston rod 33. Motive fluid supplied from any suitable source is connected by a hose or conduit with a nipple 41 attached to the rear head 42 of the feed cylinder, and this motive fluid will thus act against the rear end of the feed piston, and 40 passing through the passageways 40 and feed piston rod 33, will enter the chamber 24, the rear end of the extension 23 having suitable ports 43 to permit such passage.

Briefly described, the operation is as follows:—Motive fluid supplied through the nipple 41 will operate against the feed piston, and force it forwardly in the feed cylinder. This, it is thought, will be clear when it is considered that the plug 36 moves with the feed piston and the motive fluid acting against the same, will press it forward, thereby allowing such motive fluid to gain access to and pass freely through the passages 40 in the feed piston. Therefore if the rear end of said feed cylinder which 55 is in the form of a spur 44 is placed against a bearing or support, the motor will be advanced to its work. The motive fluid, as already explained, will enter the chamber 24, and there will thus be a constant pressure against the rear pressure surface 20 60 of the motor piston. Assuming the parts in the position shown in Fig. 1, motive fluid will also pass through the port 27, passageway 26 and port 28, thus operating against the front pressure surface 22 and driving 70 the piston rearwardly. Motive fluid in rear of the larger head 15 of the piston will exhaust through the port 29 until said port is covered. As the piston moves rearwardly, the port 27 will be covered by the piston 75 head 16, and said piston will then be driven rearwardly under the expansion of the motive fluid in the front portion of the piston chamber 6 against the pressure against the rear surface 20. At the same time, as soon 80 as the front head 15 covers the inner end of the exhaust port 29, pressure will begin to build up behind the larger head 15, or in other words, against the rear pressure surface 21. The piston, however, moves 85 rearwardly until its reduced neck 18 or groove 19 uncovers the ports 25, whereupon the motive fluid, under pressure, will pass through these ports, around the groove 19, and into the rear portion of the piston chamber 6 against the rear pressure surface 21. At this time, the enlarged head 15 has passed rearwardly to uncover the exhaust port 29 in advance of the piston. Consequently the piston will immediately reverse 90 and be driven forward on its working stroke. In this connection, with this operation it will be evident that there is constant pressure against the rear end of the feed piston, but this pressure is being alternately relieved and augmented by the action of the 100 motor piston. As already explained, there is constant pressure against the area 20, and during the forward movement of the piston, this helps to overcome the forward pressure against the feed piston. Moreover during the forward movement of the motor piston, when the ports 25 are open and the exhaust 29 in advance of the piston head 15 is open, the pressure against the rear surface 21 of the piston and against the front face of the plug 8 tends to oppose the forward pressure of the feed piston. On the other hand, when the return stroke takes place, there is, for an instant, a pressure 115 against the front surface 22 of the motor piston and against the rear face of the front head block 11, while air is then exhausted in rear of the piston head 15. This assists the feeding means to move the machine to 120 its work. As a result of these quick actions, the motor automatically overcomes the pressure of the feeding means for an instant on each stroke, and this relief is sufficient and is at the proper time to permit the machine to be rotated freely and yet it will 125 be held to its work properly, whether it is used for drilling upwardly or downwardly. In this connection, it will be noted also that a feeding piston of relatively smaller diam- 130

ter may be utilized and in the structure shown, it is of less diameter than the head 15, but greater than the head 16.

From the foregoing, it is thought that 5 the construction, operation and many advantages of the herein described invention will be apparent to those skilled in the art, without further description, and it will be understood that various changes in the size, 10 shape, proportion and minor details of construction may be resorted to without departing from the spirit or sacrificing any of the advantages of the invention.

Having thus fully described my invention, what I claim as new and desire to secure by Letters Patent, is:—

1. In apparatus of the character set forth, the combination with a motor, of feeding means for the motor comprising a cylinder member and a piston operating therein, one being connected to the motor, and means for supplying motive fluid to the feeding means, said motor comprising a cylinder member having a rear pressure surface, a 25 piston operating in the cylinder member and having two rear pressure surfaces, one of which is opposed to the surface of the cylinder member, and means for supplying motive fluid to the motor and periodically 30 introducing motive fluid between said opposed pressure surfaces of the piston and cylinder member, and thereby producing an intermittent pressure resistance to the feeding means, said motive fluid supplying 35 means maintaining a constant pressure against the other rear pressure surface of the piston.

2. In apparatus of the character set forth, the combination with a motor, of feeding 40 means for the motor comprising a cylinder member and a piston operating therein, one being connected to the motor, and means for supplying motive fluid to the feeding means, said motor comprising a cylinder member 45 having a rear pressure surface, a piston operating in the cylinder member and having two rear pressure surfaces, one of which is opposed to the surface of the cylinder member, and means for supplying motive 50 fluid to the motor and periodically introducing motive fluid between said opposed pressure surfaces of the piston and cylinder member, and thereby producing an intermittent pressure resistance to the feeding 55 means, said motive fluid supplying means maintaining a constant pressure against the other rear pressure surface of the piston, the combined areas of the rear pressure surfaces of the motor piston being greater than 60 that of the feeding piston.

3. In apparatus of the character set forth, the combination with a motor comprising a cylinder member and a piston operating therein and having rear pressure surfaces 65 of different diameters, of feeding means

connected to the motor and comprising a cylinder and a piston operating in the cylinder, said feeding piston being of less area than the larger rear pressure surface of the motor piston, means for supplying motive 70 fluid to the feeding means and to the motor, and means for distributing motive fluid to the motor piston to maintain a constant pressure against one of the rear surfaces thereof and an intermittent pressure against 75 the other.

4. In apparatus of the character set forth, the combination with a motor comprising a cylinder member having a rear pressure surface and a piston operating therein and having rear pressure surfaces of different diameters, one of which is opposed to the 80 said cylinder pressure surface, of feeding means connected to the motor and comprising a cylinder and a piston operating in the cylinder, means for supplying motive fluid to the feeding means and to the motor, and means for distributing motive fluid to the 85 motor piston to maintain a constant pressure against one of the rear surfaces thereof and an intermittent pressure against the other and against the said cylinder pressure 90 surface, said pressure surfaces of the motor and the feed piston being so proportioned that the pressure against the said combined 95 motor surfaces intermittently produces sufficient counter-pressure to the pressure against the feed piston to relieve the pressure of the apparatus against the work whereby said apparatus can be easily rotated.

5. In apparatus of the character set forth, the combination with a valveless motor, comprising a cylinder member and a piston operating therein and having rear pressure 105 surfaces of different diameters, of feeding means connected to the motor and comprising a cylinder member and a piston member operating therein, the area of the feed piston being less than the combined rear pressure 110 areas of the motor piston.

6. In apparatus of the character set forth, the combination with a valveless motor, comprising a cylinder member and a piston operating therein and having rear pressure 115 surfaces of different diameters, of feeding means connected to the motor and comprising a cylinder member and a piston member operating therein, the area of the feed piston 120 being less than the combined rear pressure areas of the motor piston, and means for delivering motive fluid under substantially the same pressure to both the feeding means and the motor.

7. In apparatus of the character set forth, the combination with a valveless motor, comprising a cylinder member and a piston member operating therein and having separate rear pressure surfaces of different 125 diameters, of feeding means connected to the 130

motor and comprising a cylinder member and a piston member operating therein, the area of the feed piston being less than the larger area and greater than the smaller area of the rear pressure surfaces of the motor piston.

In testimony whereof I have hereunto

set my hand in presence of two subscribing witnesses.
